UNITED STATES PATENT OFFICE.

JULES GERSANT, OF LARKHALL RISE, AND ARCHIBALD GEORGE BUTTIFANT,
OF LEE, ENGLAND.

MACHINE FOR FUSING SIDE SEAMS OF METAL CANS, &c.

SPECIFICATION forming part of Letters Patent No. 671,546, dated April 9, 1901.

Application filed October 22, 1900. Serial No. 33,932. (No model.)

To all whom it may concern:

Be it known that we, JULES GERSANT, a citizen of the French Republic, residing at 1 Netherford road, Larkhall Rise, in the county 5 of Surrey, and ARCHIBALD GEORGE BUTTIFANT, a subject of the Queen of Great Britain and Ireland, residing at 32 Southbrook road, Lee, in the county of Kent, England, have invented new and useful Improvements in 10 Machines for Fusing the Side Seams of Metal Cans and Like Receptacles, of which the following is a specification.

Our invention relates to improvements in machines for fusing the side seams of metal 15 cans and like receptacles by the process of fusing together within the seams the coating with which the metal from which the cans and receptacles are made, the machines being designed more especially for use in the 20 manufacture of cans and the like made from tinned iron sheet.

We attain our object by the mechanism illustrated in the accompanying drawings, in which—

25 Figure 1 is a side view of one half of the machine; Fig. 2, a part-sectional side view of the other half of the machine. Figs. 3 and 4 are respectively plans of the portions shown by Figs. 1 and 2. Fig. 5 is a front view of a 30 detail.

Supported on suitable standards *a*, attached to a base-plate or other surface *b*, we provide a table *c*, at a convenient height above the surface *b*. Below the table *c* is an air-chamber *d*, in communication with a blower of proper capacity. At the bottom of the air-chamber *d* is a stuffing-box *e*, through which passes the vertical shaft *f*, the lower end of which is supported in the foot-step *g*. To the 35 vertical shaft *f* is bolted the revoluble platform *h*, having below it the air-pipe *i*, which can rotate at the same time as the table *h* in the stuffing-box *j*, formed in the table *c*. Above the rotatable platform *h* is a gas-chamber *k*, into which gas enters through 40 holes *l* in the gas-pipe *m*, passing through the stuffing-box *n*. At the lower end of the pipe *l* is a plug *o*, stepped in a recess in the upper end of the shaft *f*. Outside the gas-chamber

k is the air-gallery *p*, communicating with the air-pipe *i* and chamber *d* by holes *q*. At intervals around the periphery of the table *h* are the saddle-shaped mandrels *r*, each having an open top covered with a steel plate *s*, on which rests the seam of the tin *t* to be operated on.

Provision is made for taking tins of more than one length, L-sectioned vertical guides *u* slidable on the horizontal guides *v*, which themselves are slidable on pins *w*, so as to allow of two of more than one diameter being held on the mandrel. These guides *u* and *v* are retainable in their required position by set-screws *w'*. Below the steel plate *s* is a burner *x*, perforated along its upper side. 65 Gas is supplied to the burner *x* from the gas-chamber *k* by the pipe *y*, having the regulating-tap *z*, and air is admitted by the pipe *A*, communicating with the air-gallery *p*, the pipe *A* being furnished with a regulating- 70 tap *B*.

The vertical shaft *f* is rotated through a portion of a complete revolution equal to its division by the number of mandrels *r* by the following means: On the shaft *f* is the ratchet-wheel *C*, with which engages the pawl *D*, carried by the link *E*, the arm *F* of which is pivoted to one end of the reciprocating rod *G*, furnished with the shoulder *H*. To the rod *G* is attached one end of a cord or equivalent *J*, 80 which passes over the pulley *K* and is provided with a weight *L*, which tends to draw the rod *G* away from the shaft *f* and so to pull the shaft *f* and table *h* around to the extent of one tooth of the ratchet-wheel *G*. The 85 rod *G* is pushed toward the shaft *f* for the purpose of taking up another tooth of the ratchet-wheel *C* by the following means: Pivoted at *M* to a plate *N*, attached to one of the supports *a*, is a lever *O*, the upper end of which is pivoted at *P* to one end of the connecting-rod *Q*, the other end of which is pivoted to the crank *R* on the shaft *S*, carrying the spur-wheel *T*. The spur-wheel *T* is operated by the pinion *U*, free to slide with one part of a 90 clutch *V* on the driving-shaft *W*, which carries the other part *X* of the clutch and also the fast pulley *Y* and the loose one *Z*. A 95

spring a' tends to draw the two parts V and X into engagement with one another, and the part of the clutch marked V is hinged at b' to the shaft c' , free to turn in end bearings d' , carried by brackets e' , attached to the table c . One of the brackets e' carries also the roller f' , on which the mandrels r rest when in position for the tin to be operated on by the pressing-roller to be hereinafter mentioned. As the mandrels r are saddle ones, a bridge-plate f^2 is provided to rest on the roller f' when the mandrel r is in position, the roller f' keeping each mandrel at the right height above the table c as it comes into position.

To the shaft c' is hinged at g' a lever h' , which is kept normally at right angles to the shaft c' by a spring i' . The lever h' has a hooked end j' to receive a pin k' , one of which is provided on each mandrel r , so as to arrest the individual mandrels as they come into position to have the seam rolled down. There is also an arm l' standing out from the shaft c' and having its outer end attached to one end of a spring m' , the other end of which is attached to the table c . The function of the spring m' is to draw over the arm l' into its normal position during the intervals between the mandrels r reaching it, which position is one of inclination in the opposite direction to that occupied when it is arresting the movement of a mandrel by catching a pin k' in its hook j' .

The seam of the can is rolled and pressed by the roller n' , carried at one end of a lever o' , pivoted at n' to one end of the reciprocating bar p' , a recess in which bar receives the other end of lever o' , the roller being kept down by the upward action of a spring q' between the lever end and the bottom of the recess. The reciprocating bar p' is free to run in the guides r' , attached to the bed c , so as to move the roller m' in and out of the tin can being operated on and press down the seam. The reciprocating bar p' is moved to and fro by the vibrating lever s , pivoted at t' to the base-plate b . The vibrating lever s' is linked to an adjustable piece u' , provided on the reciprocating bar p' , by which piece u' the throw or travel of the bar p' can be altered to adapt the machine to boxes of various lengths. The vibrating lever s' is moved to and fro by a bolt v' , passed through a slotted arm w' of the spur-wheel T . The slotted arm w' and the slot x' in the vibrating lever s' permit of the before-mentioned adjustment of the travel of the bar p' by moving the adjustable piece u' to the required extent along the bar p' .

The following provision is made for releasing a mandrel when the tin carried by it has had its seam pressed by the roller m' and its place is to be taken by the immediately succeeding mandrel bearing another tin. A rod y' is free to run to and fro in suitable guides and is provided with upstanding pins z' . At one end of the rod y' is a beak A' , pivoted

thereto at B' , and behind this beak is a spring C' , pressing against the back of beak A' . Behind the hook j' of the lever m is a projection D' , and on the adjustable piece u' and in the same plane as the pins z' is a pin which alternately strikes the pins z' . When the piece u is on its backward journey, its pin strikes one of the pins z' , so as to cause the beak A' to pull on the projection D' and draw the hook j' clear of the pin k' and so allow the mandrel to pass on to the extent the table h is moved by one tooth of the ratchet-wheel C , whereupon the lever m is pulled upward by the spring m' , to be pushed back again when the pin k' of the succeeding mandrel r comes in contact with it. The forward journey of the piece u in the meantime strikes the other of the pins z' and pushes the beak A' over the projection D' , the spring C' yielding sufficiently to allow it (the beak A') to pass and force it into position to again pull on the projection D' on the backward journey of the reciprocating bar p' .

Any suitable means may be provided to prevent or lessen concussion when the table h is moved around step by step. Such means may consist of pins E' , hanging from the platform h , which pins, as the platform moves around, press back one end of a lever F' , pivoted to a bracket G' , attached to the table C . This lever F' has attached to it one end of a spiral spring H' , the other end of which is attached to a bracket J' , fastened to the table c . When the movement of the platform h has caused the pin k' of a mandrel to push back the lever h' , the pin E' will go out of contact into the lever F' and pass on, leaving the lever F' to be drawn back by the spring H' , the outer end of the lever F' striking against the buffer K' , provided at one end of a bolt L' , carried in a bracket M' , attached to the table c .

The operation of the machine is as follows: Assuming, first, that the burners x are all in action; second, that there is a can on each mandrel r , with its "fluxed" seam resting on the plate s , and, third, that the weight L has drawn around the table h to the extent of half a tooth of the ratchet-wheel C , then the lever m will be drawn over by the spring m' and the parts v and w of the clutch disengaged and the gearing out of action. Assuming, also, that the various parts have been so assembled during construction that under the above conditions, fourth, the bar p' is at the end of its back stroke; fifth, that the lower end of the lever o is also at the end of its return stroke and out of contact with the shoulders H , and, sixth, that the beak A' is on the forward side of the lever m , then when the weight L completes the movement of the table h to the full extent of one of the teeth of the ratchet-wheel C the pin k' of one of the mandrels r will push back the lever m and revolve shaft c' sufficiently to cause the two parts v and w of the clutch to engage with

one another and set the gear in motion. The bar p' will now be pushed forward, so that the roller n' will pass into the can and press down the seam which rests on the plate s . The lever 5 o will also have pushed forward the rod G , so that the pawl takes up a position to pull around the table h to the extent of one tooth of the ratchet-wheel C when contact of the lower end of the lever o is removed from the 10 shoulder H of the rod G . On the return stroke of the bar p' , drawing the roller n' out of the tin, the pin on the adjustable piece u' will come in contact with that one of the pins z' on the bar y' , which will draw rearward the 15 beak A' and push backward the lever m , whereupon the lever m will resume its nominal position by the action of the spring m' and put the clutch v and w out of engagement, and the lower end of the lever o , having also 20 reached the end of the rear movement, the weight L will draw the rod G backward and cause the ratchet-wheel C to advance the table h , so as to bring the pin k' of another mandrel r into contact with the lever m and 25 pushing it over put the clutch parts v and w in engagement and restart the gear, whereby the roller n' will pass through the can just brought into position, and so on, each can being removed after it has passed the roller 30 and another can substituted for it.

In some cases we prefer the mandrel r to be of circular or other than saddle cross-section, so that the tin t instead of being quite outside it, with the exterior of the seam resting 35 on the plate s , may be slid over it, in order that the mandrel is inside the tin and the plate s in contact with the interior of the seam instead of with its exterior. This is essential in the case of decorated tins. In some 40 cases also we prefer to have the air-chamber d above the platform h instead of below the table c . Provision may also be made for more than one reciprocating bar p' and its accessories on one machine.

45 It is to be clearly understood that the tins operated upon by the roller n' are so operated on after the seams have been heated sufficiently to fuse the coatings within the seam, and not till then.

50 What we claim as our invention, and desire to secure by Letters Patent, is—

1. In machines for fusing the side seams of cans and the like, a table; standards supporting the said table; a revoluble platform above 55 the said table; a vertical shaft carrying the said platform; means for intermittently moving the said shaft and platform through a portion of a complete revolution; an air-chamber above or below the said platform; an air-gallery above the said platform; means for supplying air to the said air chamber and gallery; a gas-chamber above the said platform; means for conveying gas to the said gas-chamber; saddle, circular or other cross-sectioned mandrels arranged equidistantly and radially 60 around the said platform; burners within the said mandrels; regulatable means for conveying gas from the said gas-chamber to the said burners; regulatable means for conveying air from the said air-gallery to the said burners; longitudinally-adjustable guides on the said mandrels to accommodate cans of various lengths; transversely-adjustable guides on the said mandrels to accommodate cans of various diameters; a plurality of reciprocating bars; a roller at one end of each of the said reciprocating bars; means for giving intermittent to-and-fro movement to the said reciprocating bars; means for detaining the mandrels while the cans carried by them have 65 their side seams pressed by the rollers at the end of the said reciprocating bars; means for releasing the mandrels after the side seams of the cans carried by them have been pressed by the rollers at the ends of the reciprocating 70 bars; means for putting out of operation all the gear (except that for moving the above-

ers within the said mandrels; regulatable means for conveying gas from the said gas-chamber to the said burners; regulatable means for conveying air from the said air-gallery to the said burners; longitudinally-adjustable guides on the said mandrels to accommodate cans of various lengths; transversely-adjustable guides on the said mandrels to accommodate cans of various diameters; a reciprocating bar; a roller at one end of the said reciprocating bar; means for giving intermittent to-and-fro movement to the said reciprocating bar; means for detaining each mandrel while the can carried by it has 75 its side seam pressed by the roller at the end of the said reciprocating bar; means for releasing each mandrel after the side seam of the can carried by it has been pressed by the roller at the end of the reciprocating bar; 80 means for putting out of operation all the gear (except that for moving the above-mentioned platform) while one mandrel and its can succeed the immediately-preceding one in the position to have the side seam of the 85 said can pressed by the roller at one end of the said reciprocating bar; and means for preventing or lessening concussion caused by the intermittent movement of the above-mentioned platform substantially as described 90 and illustrated.

2. In machines for fusing the side seams of cans and the like, a table; standards supporting the said table a revoluble platform above the said table; a vertical shaft carrying the 100 said platform; means for intermittently moving the said shaft and platform through a portion of a complete revolution; an air-chamber above or below the said platform; an air-gallery above the said platform; means for supplying air to the said air chamber and gallery; a gas-chamber above the said platform; means for conveying gas to the said gas-chamber; saddle circular or other cross-sectional mandrels arranged equidistantly and radially 105 around the said platform; burners within the said mandrels; regulatable means for conveying gas from the said gas-chamber to the said burners; regulatable means for conveying air from the said air-gallery to the said burners; longitudinally-adjustable guides on the said 110 mandrels to accommodate cans of various lengths; transversely-adjustable guides on the said mandrels to accommodate cans of various diameters; a plurality of reciprocating bars; a roller at one end of each of the said reciprocating bars; means for giving intermittent to-and-fro movement to the said reciprocating bars; means for detaining the mandrels while the cans carried by them have 115 their side seams pressed by the rollers at the end of the said reciprocating bars; means for releasing the mandrels after the side seams of the cans carried by them have been pressed by the rollers at the ends of the reciprocating 120 bars; means for putting out of operation all the gear (except that for moving the above-

mentioned platform) while the mandrels and cans are moving into position to have the side seams of the said cans pressed by the rollers at the ends of the said reciprocating bars; and 5 means for preventing or lessening concussion caused by the intermittent movement of the above-mentioned platform substantially as described and illustrated.

In testimony whereof we have signed our names to this specification in the presence of 10 two subscribing witnesses.
